UNITED STATES PATENT OFFICE.

GEORGE U. BRAKE, OF FORT WAYNE, INDIANA, ASSIGNOR TO TOKHEIM OIL TANK AND PUMP COMPANY, A CORPORATION OF INDIANA.

LIQUID DISPENSER.

Application filed March 13, 1922. Serial No. 543,167.

To all whom it may concern:

Be it known that I, GEORGE U. BRAKE, a citizen of the United States of America, and resident of Fort Wayne, in the county 5 of Allen, and State of Indiana, have invented certain new and useful Improvements in Liquid Dispensers, of which the following is a specification.

This invention relates to improvements 10 in liquid dispensers of that class used for supplying lubricating oil to automobiles, especially at the street curb and filling stations, where the dispenser is intended to be permanently installed out of doors. It has 15 been customary in constructing dispensers for lubricating oil, when intended for permanent installation at the street curb and out of doors at filling stations, to mount a pump upon a pedestal which is anchored to 20 the ground and to connect the suction line of the pump with a tank buried in the ground, from which oil is withdrawn as needed, by actuating the pump. Such constructions and installations require consider- 25 able time and expense preliminary to operation of the dispensers, and the present invention is devised with the purpose of economical construction and simplicity in the matter of its installation. Another ob- 30 ject is to provide a self-contained oil dispensing unit in which is stored a quantity of oil to be dispensed in fractional portions, and having a sheltered pumping mechanism by which the oil is dispensed.

These objects are accomplished by the construction illustrated in the accompanying drawings, in which:—

Fig. 1 is a front elevation of a dispenser embodying the present invention, the lower 40 portion thereof being in central section:

Fig. 2 is a vertical section projected from Fig. 1;

Fig. 3 is a top plan of the housing for the dispenser, portions thereof being shown 45 broken away;

Fig. 4 is a detail view projected from Fig. 3, portions being broken away and in section;

Fig. 5 is a front elevation of the dispenser 50 in modified form; and

Fig. 6 is a vertical central section projected from Fig. 5.

The characters appearing in the description refer to parts shown in the drawings

and designated thereon by corresponding 55 characters.

The invention comprises a pedestal 1 made in the form of a cylindrical shell, the lower end of which is closed by a head 2. The pedestal has an external foot flange 3 at 60 its lower end, and a capital casting 4 which closes its upper end.

Upon the capital 4 is mounted a pumping mechanism 5, the pump cylinder 6 of which depends through the casting into the pedestal. 65 A suction pipe 7 connected with the pump cylinder extends within the pedestal to a point near the bottom thereof and is provided with a foot valve 8.

A shelter or housing for the pumping 70 mechanism is mounted upon the pedestal and consists of a stationary semicircular shell 9 secured at its lower end to the capital 4 which constitutes the base of the housing, and at its upper end to an annular flange 10 75 that depends from a dome 11. A pair of posts 12 are rigidly secured at their lower ends in the capital 4 and have supporting connection at their upper ends with the dome 11. The shell 9 partially incloses the space 80 between the capital 4 and the dome, and a movable curved door 13, which is arranged concentrically within the shell 9, is provided for closing the gap between the side terminals of the shell 9. The door 13 is sus- 85 pended from a ring 14 to which the upper edge of the door is secured, and the ring has an external flange 15 that rests upon and is supported by the annular flange 10 of the dome. The lower edge of the door 90 depends into an annular recess 4^a in the capital and is retained therein by the adjacent wall of the shell 9, and has a fixed ring 14'.

A lock 16 is positioned in an enlargement 95 17 of the flange 10, and a lug 18 on the ring 14 is adapted to be held between the bolt 19 of the lock and an upwardly projecting lug 20 on the flange 10 adjacent the lock when the door 13 is closed, and thus locking 100 the door. Also, the door has a handle 21 that projects outwardly near one edge thereof and is adapted to limit the opening movement of the door by coming into contact with the corresponding edge of the shell 105 9. A cap-screw 22 in the dome immediately over the ring 14 in the vicinity of the lock prevents the door from being raised so as to

disengage the lug 18 on the ring from locking engagement with the bolt 19.

The pumping mechanism has a crank-arm 23 provided with a handle 24 that has 5 hinged connection with the crank-arm so that the handle may be swung inwardly out of range of the door so as to permit closing of the door.

In the capital 4 is a removable fill- 10 cap 25 and also a cap 26 for a gage member 27 that extends into the pedestal. The particular construction of the fill-cap and the gage cap is immaterial to the present invention other than that they be adapted 15 when in place to prevent foreign matter to pass into the pedestal through the capital.

In the form of the invention shown in Figs. 5 and 6, the pedestal 1' is built with an extension 1^a at its lower end, in which 20 case the foot ring 3' is secured around the pedestal at a point suitably distant from the bottom thereof so that when the foot ring rests upon the surface of the ground the lower portion of the pedestal extends 25 into an excavation made in the ground for its reception. In this manner the storing capacity of the pedestal is increased without necessitating the more extensive excavation required in burying a storage tank in the 30 usual manner.

In each form of the invention the pedestal constitutes the storage means for the dispenser and its capital also constitutes the base for the housing for the pumping mechanism. In the one form the dispenser including its storage means is installed 35 above ground, while in the other form the dispenser is installed so that its storage means is partially above ground and partially imbedded in the ground.

In the operation of the invention, the fill-cap 25 is removed and the pedestal, or storage means, is filled with a supply of liquid to be dispensed, and the liquid thus 45 stored is withdrawn by manipulating the pumping mechanism in the usual manner.

When it is desired to place the dispenser

temporarily out of service, the handle 24 of the pumping apparatus is turned inwardly, and the door 13 is moved horizontally to closed position and locked, thus the space between the dome and the pedestal in which is contained the pumping mechanism is completely enclosed.

What I claim is:—

1. In a liquid dispensing unit, a storage means, a capital casting closing the upper end of said means and having an annular recess in its upper portion; a pair of posts secured in the capital and extending upwardly therefrom; a dome supported upon the tops of said posts; an annular flange in connection with the dome; a semicircular shell secured at its lower edge to the capital and at its upper edge to said flange; a ring 60 having bearing relation with said flange; a curved door, the upper end of which is secured to and supported by the ring, and the lower end of which extends into the recess in the capital and is retained therein 65 by the adjacent wall of said shell; and a pumping mechanism mounted upon the capital and having communication with the storage means.

2. In a liquid dispensing unit, a storage 75 means forming also a pedestal; a dome supported above and spaced apart from the pedestal; a pumping means positioned in the space between the pedestal and dome and having a suction pipe connection with the storage means; an annular pendant flange in connection with the dome; a semi-circular shell connecting the pedestal and flange; and a curved door having an annular ring at its top and also at its bottom, and 80 being suspended from said flange and co-operable with said shell for closing the space between the pedestal and dome.

In testimony whereof I affix my signature in presence of two witnesses.

GEORGE U. BRAKE.
